[57] CLAIM

The ornamental design for a raft anchor, as shown and described.

DESCRIPTION

FIG. 1 is a front elevational view of the raft anchor showing my new design;

FIG. 2 is a rear elevational view thereof;

FIG. 3 is a right side view thereof;

FIG. 4 is a left side view thereof;

FIG. 5 is a top plan view thereof;

FIG. 6 is a bottom plan view thereof; and,

FIG. 7 is a top perspective view thereof.

A portion of the strap in FIGS. 2, 3, 4 and 7 is shown broken away to indicate indeterminate length.
